PORTABLE ELECTRIC SAW

Robert O. Ernest, Oak Park, Ill., assignor to Sunbeam Corporation, Chicago, Ill., a corporation of Illinois

Application September 13, 1955, Serial No. 37,901

Term of patent 14 years

(Cl. D93—3)

Fig. 1 is a side elevational view of a portable electric saw embodying my new design;

Fig. 2 is a top plan view of Fig. 1;

Fig. 3 is a right side elevational view of the portable electric saw of Fig. 1;

Fig. 4 is a front elevational view of Fig. 1; and

Fig. 5 is a rear elevational view of Fig. 4.

I claim:

The ornamental design for a portable electric saw, substantially as shown.
